UNITED STATES PATENT OFFICE

ERNST MALCUS ÅGREN, OF STOCKHOLM, SWEDEN

ARRANGEMENT IN STRIKING TOOLS

Application filed December 1, 1930, Serial No. 499,359, and in Sweden February 6, 1930.

The present invention relates to striking tools of the kind in which a reciprocating striking body, which may also rotate, acts upon an anvil, which may or may not rotate, 5 in which the tool or the tool holder is inserted. The object of the invention is to enable the tool to be simply and easily dismounted so as to permit the parts exposed to the hardest wear—for instance the striking body and 10 the anvil—to be easily exchanged. According to the invention this end is achieved by supporting the anvil in the frame by means of a divided ring or sleeve engaging the anvil, said ring or sleeve co-operating with a 15 stop arranged in the frame and limiting the motion of the anvil in an axial direction, and by providing the frame, at or in the proximity of the point where the ring is supported, with a detachable part so the two parts being 20 so constructed and arranged as to allow the ring to be removed from the anvil in order to make the withdrawal of the anvil possible.

Other features of the invention will be 25 more clearly set forth in connection with the description of the embodiment shown in the drawings, in which:—

Fig. 1 shows the tool as a whole, in side view, and Figs. 2 and 3 are longitudinal sections through the bottom part of the tool on 30 the line II—II in Fig. 4, the parts occupying different positions in these two figures. Fig. 4 is a plan from below of the tool and Fig. 5 is a section on the line V—V in Fig. 3.

Referring to the drawings 1, 2 and 3 are 35 three frame parts, which are joined by means of the bolts 4. Within these frame parts the different parts of the striking tool are arranged. In the embodiment shown in the drawings the electric motor 5 is supposed to 40 rotate a sleeve 6, in which the striking body 7 is adapted to slide and is given an up and down motion partly by the influence of the shock of the striking body against the anvil 8, and partly by an energy storer or other 45 arrangement, for instance balls 9 acted upon by centrifugal force. The anvil 8 which comprises a body portion and an enlarged head, is supported partly in the top part 10 of the frame part 2 and partly in the bottom 50 part 11 of said frame part and at this last-

mentioned point the bearing is provided by means of a divided ring or sleeve 12, which extends into an annular groove in the anvil.

The bearing of the frame part 11 is somewhat longer than the height of the ring 12 55 so as to allow an axial displacement to be given to the ring and, thus, to the anvil. In order to limit the amplitude of this axial displacement and thus to prevent the anvil from being pressed too far upwards in the direction towards the striking tool against the action of a spring 13, there is a stop 14 in the frame part at one side of the bearing point of the ring 12.

When the tool is assembled the different 65 parts occupy the position shown in Fig. 2. When it is desired to remove, for instance, the anvil 8, the nuts 15 on the bolts 4 are removed and the bolts are turned a little so that the T-shaped heads 16 are brought out of engagement with the openings 17 in the frame part 1 and the bolts 4 may be removed and, thus, the frame part 3 may be brought downwards 70 and the frame part 1 upwards in relation to the frame part 2, whereby the ring or sleeve 12 is freed and may be removed from the anvil. The anvil is now free so that it may 75 be drawn upwards out of the frame part 2 and the striking body 7 may be drawn downwards out of the frame part 1, as readily set forth by Fig. 3.

When assembling the tool the operation described is reversed. Of course, it is not necessary that the different 80 frame parts should be kept together, in the way now described, by means of bolts provided with hook-shaped heads. Instead 85 ordinary bolts, for instance, may be used which are screwed into suitable fastenings in the frame or a part connected therewith.

The bearing and tightening arrangements 90 for the striking body, the anvil and the tool 19 inserted in the anvil may also be constructed in many different ways, as the arrangements, excepting the divided bearing ring 12, form no essential part of this invention. 95

The striking body, the anvil, and the balls 9 for moving the striking body against the anvil may be arranged as described in the patent specifications Nos. 1,776,057 and 1,816,104. 100

Having now particularly described the nature of my invention and the manner of its operation, what I claim is:—

1. A striking tool of the character described including a striking body, an anvil having a body portion and an enlarged head, a sectional ring detachably engageable with said body portion, a plurality of frame sections and means for releasably fastening said frame sections together in longitudinal alignment, one of said frame sections having a bore serving as a guide for one end of the anvil body and another of said frame sections having a bore through which the other end of the anvil body passes, said bores at adjacent ends of said frame sections being both enlarged to form a chamber to receive and guide said sectional ring, one end of said chamber constituting an abutment for the sectional ring to limit the axial movement of the anvil towards the striking body, while when said frame members are released and moved apart the sections of the ring are in alignment with and removable through the resulting peripheral opening in the chamber to permit withdrawal of the anvil.
  2. A striking tool as claimed in claim 1 including a spring arranged about the anvil and bearing against a part of one of the frame members and against the sectional ring, said spring acting as a balancing spring when the tool is in operation and acting also to thrust the ring into position for removal when the frame sections are released and moved apart.
  3. A striking tool as claimed in claim 1 wherein the anvil is provided with a groove and wherein the ring consists of two parts detachably engaged with the groove.
- 40 In testimony whereof I affix my signature.

ERNST MALCUS ÅGREN.
